TIPPING-OFF APPARATUS

Walter J. Geiger, Cleveland Heights, and Reginald J. Ayres, University Heights, Ohio, assignors to General Electric Company, a corporation of New York

Application August 21, 1940, Serial No. 353,524

9 Claims. (Cl. 176—3)

Our invention relates to a method and apparatus for sealing the openings or conduits in the enclosing envelopes of electric lamps and similar devices through which openings or conduits the said devices are exhausted and gas filled. More particularly, our invention relates to a so-called tipping-off method and apparatus for closing and sealing the vitreous exhaust or pump tube which is in communication with the interior of the envelope of a lamp or similar device.

It is the usual practice to provide the enclosing vitreous envelopes of electric lamps, radio tubes and other similar devices with a vitreous exhaust tube or other vitreous tubulation extending from said envelope through which the envelope is exhausted and filled with gas, the said tube or other tubulation being subsequently sealed, usually by fusing it. Some difficulty is experienced in performing the sealing or "tipping-off" operations at the high speed of operation of the automatic exhaust apparatus with which they must be associated. Such difficulties are due largely to variations in thickness and composition of the vitreous walls of the exhaust passage which affect the rate of heating thereof and the time required to render them plastic, and to variations in the heat supplied by the sealing apparatus. However, most difficulty is experienced when the lamp or similar device contains gas at greater than atmospheric pressure as the vitreous walls cannot then be heated to the temperature ordinarily permitted since they could not withstand the gas pressure without blowing out.

One object of our invention is to provide a method and apparatus for determining the heated condition of the vitreous walls of the exhaust passage in order to permit said passage to be closed and sealed more readily than heretofore. Such method and apparatus permits more rapid heating of the vitreous walls of the passage and mechanical working of said walls, since accurate control of the heating operation is afforded and the proper operation of the mechanical means is assured.

Another object of our invention is to provide a method and apparatus for closing and sealing the exhaust passage in a vitreous portion of a device having a gas filling greater than the sub-atmospheric pressures normally used for lamps and similar devices. The difficulty with which the exhaust passage is closed increases greatly when the gas pressure approaches and exceeds atmospheric pressure as some mechanical means

must be provided to bring the walls of said passage together. The mechanical means must be timed to operate after the vitreous walls of the passage are heated to a degree which renders them plastic and workable but before said walls are heated to a degree where they no longer have sufficient strength to withstand the gas pressure within the envelope. The period of time during which the vitreous walls are between these different degrees of heat is extremely short in high speed apparatus and the difficulty of determining the condition thereof is greatly increased. When the gas pressure in the device approaches atmospheric pressure said device must ordinarily be cooled before the tipping-off operation is brought about in order to reduce the pressure as much as possible. To operate in this manner ordinarily takes up two of the sixteen stations of the exhaust apparatus and limits the production of said apparatus. Our invention provides a method and apparatus for ascertaining the individual heat conditions and proper mechanical pinching apparatus under these particular conditions of operation.

Another object of our invention is to provide a method and apparatus for closing and sealing a portion of the exhaust passage without actual contact with the heated vitreous walls thereof.

Still further object of our invention is to provide apparatus for closing, sealing and tipping-off the vitreous exhaust tubes extending from the envelopes of such devices at a high rate of speed, in combination with the high speed rotating type of exhaust apparatus.

Other objects and advantages of our invention will appear from the following detailed description of species thereof and from the drawings.

In the drawings, Fig. 1 is a plan view of one species of tipping-off apparatus comprising our invention in combination with the adjacent portions of an exhausting and gas filling apparatus; Fig. 2 is a side elevation of the essential parts of the tipping-off apparatus on a larger scale; Fig. 3 is a perspective view of lamp positioning mechanism associated therewith; Fig. 4 is an end elevation of pinching and operating portions of our apparatus; Fig. 5 is a side elevation of the pinching portion of the apparatus from which portions have been broken away; Fig. 6 is a perspective view of a clutch forming part of the operating portion of the apparatus; Fig. 7 is a perspective view of lamp supporting and lifting portions of a modification of our invention; Fig. 8 is a side elevation of a second

modification thereof; and Fig. 9 is a perspective view of an exhaust tube sealed by said second modification.

In Fig. 1, four adjacent heads 10 of the exhausting and gas filling apparatus appear, although it will be understood that duplicate heads are mounted at regular intervals in a circular path adjacent the periphery of the turret 11. Each of the heads 10 accommodates a single incandescent lamp 12, in this instance, and provides an exhaust port for receiving the vitreous exhaust tube 13 of said lamp 12 as shown in Fig. 2. The turret 11 is indexed in a counter-clockwise direction and advances the heads 10 from station A, the loading station, through station B and others (not shown) at which the exhausting and gas filling operations are automatically brought about, and finally carries said head 10 to stations C and D. Such apparatus is preferably that disclosed in the Patterson Patent 1,662,045 and provides a driven shaft (not shown) below the turret 11 for operating the parts thereof in proper time relation to the indexing movements of said turret 11.

A lamp 12 is placed in the head 10 at station A by a movement which inserts the end of the exhaust tube 13 (Fig. 2) into the central openings in the guide 14 and the compression rubber 15, the movement being completed when said end rests on the shoulder 16 of the body 17 of said head 10. The compression rubber 15 engages the exhaust tube 13 only with sufficient pressure to keep the lamp 12 in an upright position and is not caused to seal said tube 13 in the body 17 until station B is reached.

In the indexing movement which follows, said lamp 12 is carried into station B and into the space between the opposite legs of the yoke 18 as indicated in Fig. 3. The yoke 18 is a portion of a positioning means at this station which lifts and thereby re-positions said lamp 12 so that the lower end of the seal 19, the point of reference, is at a definite level. Such apparatus is not always required as the length of the exhaust tube 13 can often be controlled with sufficient accuracy to establish the position of said lamp 12 as desired. The said positioning means essentially comprises plates 20-21 on the opposite legs of the yoke 18 which are raised to a fixed level during every cycle of operation of said means. The plates 20-21 are located at opposite sides of the path of movement of the exhaust tube 13 and are actuated through a corresponding movement of the slide 22 which is connected to said yoke 18 through the rod 23. The slide 22 is located in the ways of the bracket 24 extending from a portion of the frame of the exhaust machine below the turret 11 and takes a position determined by the particular portion of the wedge shaped cam 25 located below the roller 26 on the lower end of said slide. The cam 25 is mounted on the arm 27 attached to the vertical shaft 28 in the bracket 24 and is actuated by the usual form of cam-operated means (not shown) on a driven shaft of the exhaust machine connected to said arm 27 through rod 29.

The plates 20-21 engage the lower surface of the seal 19 of the lamp 12 and hold said lamp 12 in this newly established position until the compression rubber 15 is squeezed to grip the exhaust tube 13. This latter operation is performed by turning the cap 30 so that it is screwed down on the body 17 of the head 10 and causes the guide 14 to squeeze the compression

rubber 15 and is brought about either by manual adjustment of the cam 25 on said cap 30 or by mechanical adjustment of said cam 25 by a portion (not shown) of said exhaust machine. The compression rubber 15 expands laterally so that it seals the exhaust tube 13 in the body 17 and grips said tube 13 with sufficient force to resist its withdrawal. Both the plates 20 and 21 are returned to their former position before the head 10 and lamp 12 are indexed from this station. In instances where the exhaust machine provides a head having rubber connection means of different construction into which the exhaust tube 13 must be forced, the upward motion of the positioning means may be sufficient to move the lamp 12.

Succeeding indexing movements of the turret 11 carry the lamp 12 to other stations for periods which permit it to be repeatedly exhausted and flushed, and finally exhausted and gas filled in the usual manner, and finally carries said head 10 to station C. While at this station, C, that portion of the exhaust tube 13 which is to be closed and sealed is preheated by the flames from the burners 32 and 33 which normally lie out of the path of movement thereof but are carried into operative relation to the exhaust tube 13 between the indexing movements of the head 10. The burners 32 and 33 are mounted on opposite ends of the U-shaped manifold 34 and are moved into position by the rocking motion of the shaft 35 to which said manifold 34 is connected by the clamp 36 and the vertically disposed rod 37. The shaft 35, in turn, is held by the sidewardly extending arm 38 of the bracket 39 and is operated through arm 40, rod 41 and lever 42 which are portions of means actuated by a cam (not shown) on a driven shaft of the exhaust apparatus. The bracket 39 is a stationary member, as it is mounted on a portion of the frame (not shown) of the exhaust apparatus below the turret 11.

In the course of the movement of the burners 32 and 33 to the operative position, the metal shield 43, which is attached to the top surface thereof, is carried under the lamp 12 and into engagement with the lower extremities of the seal 19 thereof which prevent further motion and positions the burners 32-33 longitudinally along the exhaust tube 13. In addition to its positioning action, the shield 43 also serves to direct the splash and heat of the pre-heating flames away from the upper portion of the exhaust tube 13 and the other parts of the lamp 12. The gas and air mixture used by the burners 32 and 33 in this instance is conducted to the manifold 34 through the flexible hose 44.

The period of operation of the burners 32 and 33 is relatively short and the exhaust tube 13 is heated to some point below that at which it becomes plastic and would change shape due to a difference between internal and atmospheric pressures. The lamp 12 shown contains gas at greater than atmospheric pressure and the heating of the exhaust tube 13 must not be such that said gas pressure can cause it to bulge. In every instance, the gas pressure within the lamp 12 is at a greater pressure than it will finally be because of the heat said lamp 12 contains at this time.

After a predetermined period at station C, the exhaust head 10 carries said lamp 12 to station D where the pre-heated portion of the exhaust tube 13 is again heated but this time only the exact amount required to bring said tube 13 to

a very definite degree of plasticity. The exhaust tube 13 must not soften to such a point that the gas pressure within the lamp 12 can cause an opening to be blown therethrough or cause a substantial change in shape thereof but must be carried to such a point that it can be pinched shut by the jaws 45-46 (Figs. 1 and 2). To control the heating operation this closely is extremely difficult and necessitates separate control for each case due to variations in the amount of heat in the exhaust tube 13 at the start of the tipping operation and the heating effect of each of the different burners and differences in the size, distribution and composition of said exhaust tube 13. In many instances, the rate of indexing the exhaust heads 10 is so rapid that additional pre-heating burners must be placed at the station ahead of station C since the operating period of the apparatus at station D is shared by the burners 47-48 and the pinching jaws 45-46. The burners 47-48, as shown in Figs. 1 and 4, are each mounted on one end of rigid pipes 49 and 50, respectively, which pipes are held by a plurality of arms 51 extending from the metal block 52 which in turn is supported by the metal supports 53 on the extending portion 54 of the frame of the exhaust machine. The combustible gas mixture enters the opposite ends of the pipes 49-50 through the rubber hose 55, and preferably is made up of gases producing more heat than in prior instances. The burners 47-48 and pipes 49-50 are stationary members since they are located out of the path of movement of the head 10 and lamp 12 from station C to the unloading station D.

The heating period of the burners 47-48 is controlled by means engaging the lamp 12 during its movement to station D and comprises the pressure member or cup 56, which receives the upper portion of the exhaust tube 13 and the seal 19 of said lamp 12, and the resilient clip or holder 57 which receives the neck of the lamp bulb at the end of said movement. The cup 56 is mounted on the outer end of the arm 58 and is held at a position which permits the seal 19 to pass over the slotted bottom 59 thereof and is immediately moved up until said bottom 59 is against the lower extremity of said seal 19. The arm 58 is attached to the shaft 60 which is supported by the arms 61-61 on opposite sides of the block 52 and is actuated by the arm 62 on the end of said shaft 60 which is connected to the rod 63 and the spring 64. The rod 63 is the only illustrated portion of the cam controlled operating means actuated by the main drive shaft of the exhaust apparatus and at this time adjusts said rod 63 so that the contracting force of the spring 64 is responsible for the movements of the cup 56. In this manner, a known amount of upward pressure is exerted against the cup 56 and the upper portion of the lamp 12, and a known tension is placed in the exhaust tube 13. Very soon thereafter, the exhaust tube 13 softens to a point where it is lengthened by the tension under which it is kept, and the resulting upward movement of said cup 56 carries the end of the screw 65 on the arm 62 (see Fig. 5) downward against the control pin 66 of the completely enclosed switch 67. The said switch 67 is a commercial type of single-pole single-throw switch made by The Micro Switch Corporation of Freeport, Illinois.

The switch 67 indirectly controls the operation of the squeezing or pinching jaws 45-46 and, 75

when closed in this manner, causes the solenoid 68 (Fig. 4) to bring about the engagement of the clutch 69 of the operating apparatus for said jaws. At this time, the exhaust tube 13 has not softened sufficiently to permit any gas pressure in the lamp 12 to materially expand said exhaust tube 13 but said tube 13 has softened to a point where it can be worked satisfactorily by the jaws 45-46. In instances where the gas pressure in the lamp 12 is so low as to be below atmospheric pressure, this apparatus is adjusted so that the pinching or squeezing occurs when the exhaust tube 13 is softened the desired degree.

The movable armature 70 actuated by the solenoid 68 is connected to the arm 71 of the clutch 69 by the bar 72 and is raised by said solenoid 68 until the arm 71 takes the position shown in Fig. 6 and the movable dog 73 is permitted to shift and engage the teeth 74 on the driven clutch disk 75. The arm 71 is pivoted on the pin 76 extending from the bracket 77 on one portion of the frame and is lifted from the transverse slot 78 in the dog 73 so that the expansion of the spring 79 contained within a well therein can move said dog 73 longitudinally in ways in the idling disc 80 of the clutch 69. The spring 79 also bears against a pin 81 extending outward into said ways in the idling disc 80 and quickly advances said dog 73 beyond the face of said disc 80 and into the path of one of the teeth 74 on the adjacent face of the driven disc 75. The idling disc 80 is fastened to a shaft 82 supported by the bracket 83 attached to a portion of the frame while the corresponding driven disc 75 is fastened to the shaft 84 supported by the bracket 85. The driven disc 75 receives its rotative force from an electric motor and speed reducer (not shown) which are connected thereto through the chain 86 and sprocket 87 and provides a source of power rotating faster than the drive shaft of the exhaust apparatus.

The first result of the engagement of the clutch 69 is to move the jaws 45-46 radially inward of the turret 11 into operative relation to the exhaust tube 13 since both jaws are pivotally mounted on the pins 88-88 (Fig. 1) extending from the slide 89 (Fig. 4) and said slide 89 and the secondary slide 90 (Figs. 1 and 4) are moved forward as a unit by the lever 91 which is pivotally connected to the secondary slide 90 by pin 91'. The lever 91 is pivoted on the pin 92 extending from the metal supports 53 and is actuated by the crank motion of the pin 93 in the disc 94 on shaft 82 which motion is transferred to the lever 91 through the rod 95. The slide 89 moves forward until the nuts 96 on the stud 97 extending from the end thereof engage the yoke 98 on the end of the block 52 whereupon the continued pressure of the lever 91 moves the sub-slide 90 in the ways in slide 89 causing the jaws 45-46 to pivot and close. The sub-slide 90 is held in these ways by the cover plate 99 and, when moved separately from slide 90, respositions the post 100, which extends upward through a slot in the cover plate 99, with respect to the slide 89 and operates the toggle joint formed by the links 101 to thereby pivot and close the jaws 45-46. The radially inward movement of post 100 stretches the spring 102 extending between post 100 and the post 103 extending from the cover plate 99, and causes the jaws 45 and 46 to bring the dies 104-104' into engagement with the heated and now plastic portion of the exhaust tube 13. The dies 104-104' squeeze and pinch the walls of the exhaust tube 13 together until the exhaust pas-

sage therethrough is completely blocked off the said dies pressing a comparatively large portion of the opposite walls of said tube 13 together so that a very strong and reliable seal is formed. The walls of the exhaust tube 13 are sufficiently plastic to seal together and are very quickly cooled by the dies 104-104' so that no further change in shape can occur.

It is preferred that the heating cycle end when the jaws 45-46 are closed, and accordingly, shields 105-106 are dropped into position before the burners 47 and 48 to deflect the flames. The shields 105-106 are mounted on the arms 107 and 108 respectively which are pivoted on the shaft 80 and are connected together by the cross bar 109 which causes them to operate as a single unit. Operation of the arms 107-108 is brought about by the separate motion of the sub-slide 80 in that it carries the cam 110 against the end 111 of arm 108 and forces it upward, thus lowering the shields 105-106.

The dies 104-104' are preferably provided with matching ridges 112 which can be caused either to groove the exhaust tube 13 so that it can be broken off at a predetermined point or to shear off said exhaust tube 13 as shown. The latter arrangement is preferred in that the lamp 12 is released from the head 10 at this time and, while still held by the clip 57, is lifted by further movement of said clip 57 and cup 56 caused by the further contraction of the spring 64 until the lamp is placed in a discharge chute (not shown) located above this apparatus.

The apparatus is immediately returned to its original position by the clock-wise movement of the lever 91 on the downward stroke of the pin 93. A repeat operation would then occur except that the mechanism controlled by the armature 10 of solenoid 68 is disconnected from the clutch 69 which automatically disengages and stops said pin 93 at the bottom of its stroke. The disconnecting action is brought about by the engagement of the cam 113 (see Fig. 6) on the idling disc 80 of said clutch 69 with the roller 114 on the end of the lever 115 which is connected to bar 72 (which is, in turn, connected to armature 10 of solenoid 68) through the link 116 and which shifts said bar 72 so that the vertically elongated portion of the inverted L-shaped slot 117 is about the pin 118. The arm 71 is then forced down by the expansion of the spring 119 which is located between it and the immediate lower surface of the frame and further rotation of the idling disc 80 carries a relatively narrow exposed portion of the groove 78 in the dog 73 against the wedge shaped end of arm 71. Still further movement of the idling disc 80 causes the end of the arm 71 to force the end of the dog 73 outward and the opposite end away from the teeth 74 of the driven disc 75. At the end of the movement, the dog 73 engages the shoulder 120 on the arm 71 and stops all movement and the switch 67 is again opened so that the solenoid 68 permits the rod 12 to fall to its former position. The cam 113 in this interval passes beyond the roller 114 and the full pressure of the leaf spring 121 which extends down from the immediate frame portion is free to move the lever 115 and rod 72 back to its earlier position as the pin 118 is again located in the wider or lateral portion of the slot 117. In the return movement of the sub-slide 80, the cam 110 is carried away from the end 111 of lever 108 and other means are provided for keeping the shields 105-106 in position before the burners 47-48. Such means consists of the

rod 122 (Fig. 4), which extends between lever 107 and the collar 123 on the vertically disposed push rod 124, and other means actuated by a cam (not shown) on a driven shaft of the exhaust machine which moves the push rod 124. After this particular head 10 is indexed out of station D and the succeeding head 10 is about to move into said station, the push rod 124 is re-adjusted so that the shields 105-106 are moved upward and no longer cut off the flames from the burners 47-48. The exhaust head 10 is then indexed to the loading station where the cap 30 is turned so as to release the pressure on the compression rubber 15, and the stub of the exhaust tube 13 is taken therefrom.

In instances when it is not desired to remove the lamp 12 directly after the pinching operation as when the exhaust tube 13 is not completely sheared off, it is preferred that the modification of the apparatus shown in Fig. 7 be used. The modification provides a movable plate 125 in combination with each of the exhaust ports 10 which limits the extent to which the exhaust tube 13 can be inserted therein and definitely establishes the position of the lamp 12. The lamp 12, in this instance, is pushed down, upon insertion, until the seal 19 rests on the asbestos pad 126 on the plate 125 at which time it is also located between the three padded pins 127 of holding means also combined with the exhaust ports 10. The plate 125 is mounted on the arm 128 which is pivotally mounted on the pin 129 extending from the bracket 130 whereas the pins 127 are attached to the plate 131 which is attached to the upper part of the bracket 130. The bracket 130 in turn is mounted on the upper end of a post 132 held by an extending portion 133 of the turret 11 adjacent the exhaust port 10. The position of the plate 125 must be established so that it will be properly aligned with the other portions of my apparatus when indexed into the station occupied thereby and is under the control of the stop screw 134 carried by the extending portion 133 of the turret 11 against which the bottom of the bracket 128 rests. A helical spring 135 is located between plate 125 and plate 131 in order to keep said plate 125 in the lower position.

That portion of the modified apparatus mounted on the turret 11 is of no further use until all exhausting and gas filling operations have been completed and the exhaust port 10 has been indexed into a station corresponding to station D. At this time, the exhaust tube 13 is heated by the flames from burners (not shown) corresponding to those used in the prior instance and is placed under tension by the upward movement of the plate 125 which is actuated by a corresponding motion of arm 136 carrying said arm 136 into engagement with the roller 137 on the pin 138 in outer portion of said plate 125. The arm 136 corresponds to the arm 58 of the prior apparatus in that it applies a definite force to the exhaust tube 13 which causes it to stretch when it is sufficiently plastic to be worked and in that it causes the pinching jaws (not shown) to close at the moment the stretch occurs. The burners 47-48 and the operating means for arm 58 are preferably used in combination with this latter apparatus although said burners must be arranged in a different manner to be out of the path of movement of the apparatus on the turret 11 as it is moved to and from the modified apparatus. The extent to which the exhaust tube 13 is stretched is governed by the stop screw 139

in the bracket 130 which limits the upward movement of the plate 125. The pinching jaws are also preferably those of the prior apparatus but are only closed such an amount that the exhaust tube is flattened and grooved, and not until it is completely sheared off. The posts 127 and the plate 125 must then hold and support the lamp 12 which is immediately indexed from this station. During the indexing movement, the roller 137 passes onto the track 140 which is arranged so that the plate 125 is kept up against the seal 19 of said lamp 12. The usual forms of mechanisms for unloading the lamp 12 are sufficiently strong to automatically cause the exhaust tube 13 to be broken off at the weakened or grooved point.

The modification of our invention shown in Fig. 8 is located adjacent the tipping-off station of the exhaust and gas filling apparatus and is comprised of a plurality of burners 141 (only one of which appears in the drawings) which direct flames against the exhaust tube 13. The burners 141 heat a selected portion of said exhaust tube 13 adjacent the seal 19 of the lamp 12 and can, if desired, be movably mounted so as to be shifted to and from operative relation to said exhaust tube 13 very much as in our other apparatus (Fig. 1). In this instance the exhaust tube 13 is subjected to a definite torsional strain by the rotational efforts of the vacuum cup 142 which engages the top of the lamp 12 so that when the said tube finally reaches a temperature where it is no longer strong enough to resist the rotational force, it then starts to twist. The twisting movement indicates that the exhaust tube 13 is heated to a safe temperature to be tipped off and is continued until the lamp 12 is turned a number of complete revolutions and an appreciable length of said exhaust tube 13 is twisted. At the moment the lamp 12 and the vacuum cup 142 begin to rotate, it is preferred that the heating effect of the burners 141 be discontinued either by a reduction in the amount of the combustible gas mixture supplied thereto or by the insertion of shields between said burners 141 and the exhaust tube 13. The walls of the exhaust tube 13 are, at such times, sufficiently heated to be drawn into contact with each other by the twisting motion and seal to each other before cooling takes place. The twisting force is very definitely established in that it results in the deformation of the exhaust tube 13 which is the controlling element in the method and is therefore directly responsible for the timing of the operations of the apparatus which close the passage in said exhaust tube 13.

The period of operation of the burners 141 and the cup 142 starts when the turret 11 carries the exhaust port 10 holding the lamp 12 to the station shown as the exhaust tube 13 is then placed in operative relation to said burners 141, and the cup 142 is immediately lowered onto the lamp 12. The vertical movement of the cup 142 is, however, separately produced and is brought about through a corresponding movement of the spindle 143, the arm 144 and the vertical standard 145 all of which are fastened together so that they move as a unit. The standard 145 is located out beyond the edge of the turret 11 and it directly engages apparatus (not shown) actuated by the cam shaft (also not shown) of the exhausting and gas filling apparatus below the turret 11 which makes it possible to carry the cup 142 to and from engagement with the lamp 12 in proper time relation to the movements of

the exhaust port 10. The cup 142 must grip the top of the lamp 12 with sufficient tenacity to cause it to turn therewith and is therefore constructed so as to seat firmly on the top of the lamp 12 and pull thereon with the suction force of vacuum. The universal joint formed by the head 146 of said cup 142 and the flared fitting 147 on the end of said spindle 143 permits said cup 142 to adjust itself to the top of the lamp 12 whereas the gasket 148 of asbestos or the like seals the juncture between said cup 142 and the lamp 12. A spring 149 located between a post in the spindle 143 and a second post 150 in the head 146 of the cup 142 holds said cup 142 in place during the intervals it is not in contact with the lamp 12. The spring 149 is located in the hollow center of the spindle 143 which provides for the vacuum connection to the cup 142 in that it is closed at the top by the plug 151 and is connected to the chamber 152 in the arm 144 by the openings 153 in the side walls of the spindle. Stuffing boxes 154 at opposite ends of the opening in the arm 144 holding the spindle 143 prevent leakage thereabout whereas the pipe nipple 155 and the flexible hose 156 connect the vacuum source (not shown) to said chamber 152.

The rotational force with which the lamp 12 is turned is transferred to the cup 142 from the spindle 143 by the pin 150 which is carried by the head 146 of the former and which is located in a slot in the fitting 147 of the latter. Said force originates in the shaft 157 which is coupled to said spindle 143 through the bevel gears 158 and 159. The shaft 157 is held in bearings in the arm 144 and is turned by the gravitational pull of the weight 160 which hangs from the rope 161 wound about the drum 162 on the outer end of said shaft 157. The size of the weight 160, of course, can be varied so as to produce the definite rotational force desired and is selected after consideration of the gas pressure in the lamp, the size and strength of the exhaust tube and the rapidity with which said exhaust tube is heated. As hereinbefore stated, the exhaust tube 13 must not be heated until it no longer has sufficient strength to remain intact but must be heated to some point where it can be worked. The manner in which the apparatus operates must also be taken into account and in some instances it may be desirable to use an exhaust tube of greater than normal wall thickness to properly meet all operating conditions.

Both the suction and the twisting operations are desirable only when the cup 142 is in engagement with the lamp 12 and means can be provided in combination with the cam shaft of the exhausting and gas filling apparatus for confining these operations to the proper periods. A vertical shaft 163 within the hollow standard 145 and the inter-meshing bevel gears 164 and 165 provide the means of connecting the cam shaft actuated means to the shaft 157 of the twist producing means. The shaft 163 and the gears 164 and 165 also provide means of turning the drum 162 and rewinding the rope 161 after each succeeding cycle of operation. The exhaust tube 13 is twisted a sufficient number of times to cause an appreciable portion of said exhaust tube 13 to be drawn together, as shown in Fig. 9, and ordinarily must be twisted four to ten times to produce the result desired.

As a method of controlling the tip shape, it is sometimes desirable to do some stretching during the twisting operation and means can be provided for raising the vacuum cup 142 to pro-

duce this operation. Such means can be operated from a cam on the cam shaft of the exhausting and gas filling apparatus and can actuate the hollow standard 145. The exhaust tube 13 now is drawn down to such a size that it 5 may not have sufficient strength to support the lamp 12 and the plate 166 and posts 167 which extend therefrom are depended upon to support said lamp 12. The posts 167, of which there are three in number, are located about the neck of the lamp 12 as in the prior instance shown in Fig. 7 and are fastened to the plate 166 which, in turn, is attached to the arm 168. Said arm 168 is pivotally attached to the block 169 by the pin 170 in the manner of the arm 128 in Fig. 7 and is swung upward so that plate 166 is kept against the seal 19 of the lamp 12 by the expansion of the spring 171. A well in the arm 168 is provided to hold the spring 171 which butts against the block 169. After the closure is made 10 by twisting, the exhaust tube 12 can be severed by cold cutting or by fires, depending on the shape of tip desired. Either of these operations 15 can occur at a succeeding station taken by the head 18 if desired.

What we claim as new and desire to secure by Letters Patent of the United States is:

1. The method of sealing an exhaust tube 20 extending from a sealed envelope containing gas at a pressure above that of the surrounding atmosphere which comprises heating a portion of the exhaust tube while the said tube portion is exposed to the said surrounding atmosphere, mechanically exerting on said tube, while it is being heated, an external force to produce a strain in said tube of sufficient magnitude to rapidly deform the heated portion of the tube when it becomes sufficiently plastic to be thus deformed but before said tube portion becomes sufficiently 25 plastic to be ruptured by the internal gas pressure, and thereafter preventing additional heating of said tube which would render it sufficiently plastic to be ruptured by said internal gas pressure.

2. The method of sealing an exhaust tube 30 extending from a sealed envelope containing gas at a pressure above that of the surrounding atmosphere which comprises heating a portion of the exhaust tube while the said tube portion is exposed to the said surrounding atmosphere, mechanically exerting on said tube, while it is being heated, an external force to produce a strain in said tube of sufficient magnitude to rapidly deform the heated portion of the tube when it becomes sufficiently plastic to be thus deformed but before said tube portion becomes sufficiently 35 plastic to be ruptured by the internal gas pressure, and squeezing the said heated and deformed tube portion immediately after the deformation has started so as to seal it and preventing additional heating of said tube which would render it sufficiently plastic to be ruptured by said internal gas pressure.

3. The method of sealing an exhaust tube 40 extending from a sealed envelope containing gas at a pressure above that of the surrounding atmosphere which comprises heating a portion of the exhaust tube while the said tube portion is exposed to the said surrounding atmosphere, mechanically exerting on said tube, while it is being heated, an external force to produce a twisting strain in said tube of sufficient magnitude to rapidly deform the heated portion of the tube when it becomes sufficiently plastic to be thus deformed but before said tube portion becomes 45

sufficiently plastic to be ruptured by the internal gas pressure, and thereafter preventing additional heating of said tube which would render it sufficiently plastic to be ruptured by said internal gas pressure.

4. Apparatus for sealing an exhaust tube 50 extending from a sealed envelope containing gas at a pressure above that of the surrounding atmosphere comprising means for heating a portion of said exhaust tube while the said tube portion is exposed to the said surrounding atmosphere, mechanical means exterior of said envelope exerting a continuous strain on said tube while it is being heated tending to deform it, the said strain being of sufficient magnitude to rapidly deform the heated portion of the tube when it becomes sufficiently plastic to be thus deformed but before said tube portion becomes sufficiently plastic to be ruptured by the internal gas pressure, and means for preventing additional heating of said tube which would render it sufficiently plastic to be ruptured by said internal gas pressure.

5. Apparatus for sealing an exhaust tube 55 extending from a sealed envelope containing gas at a pressure above that of the surrounding atmosphere comprising means for heating a portion of said exhaust tube, while the said tube portion is exposed to the said surrounding atmosphere, and mechanical means exterior of said envelope exerting a continuous strain on said tube while it is being heated tending to deform it, the said strain being of sufficient magnitude to rapidly deform the heated portion of the tube 60 when it becomes sufficiently plastic to be thus deformed but before said tube portion becomes sufficiently plastic to be ruptured by the internal gas pressure, clamping jaws arranged to pinch the heated and deformed tube portion immediately upon deformation thereof, means operative upon deformation of said tube portion for causing said clamping jaws to close upon said tube portion, and means for preventing additional heating of said tube which would render it sufficiently plastic to be ruptured by said internal gas pressure.

6. Apparatus for sealing an exhaust tube 65 extending from a sealed envelope containing gas at a pressure above that of the surrounding atmosphere comprising means for heating a portion of said exhaust tube, mechanical means exterior of said envelope exerting a continuous strain on said tube while it is being heated tending to deform it, the said strain being of sufficient magnitude to rapidly deform the heated portion of the tube before said tube portion becomes sufficiently plastic to be ruptured by the internal gas pressure, clamping jaws arranged to pinch the heated and deformed tube portion immediately upon deformation thereof, and means actuated by movement of the said mechanical strain-exerting means for causing said clamping jaws to close upon said tube portion.

7. Apparatus for sealing an exhaust tube 70 75 extending from a sealed envelope containing gas at a pressure above that of the surrounding atmosphere comprising means for heating a portion of said exhaust tube, mechanical means exterior of said envelope exerting a continuous strain on said tube while it is being heated tending to stretch it, the said strain being of sufficient magnitude to rapidly stretch the heated portion of the tube before said tube portion becomes sufficiently plastic to be ruptured by the internal gas pressure, clamping jaws arranged to pinch

the heated and stretched tube portion immediately upon stretching thereof, and means actuated by movement of the said mechanical strain-exerting means for causing said clamping jaws to close upon said tube portion.

8. Apparatus for sealing an exhaust tube extending from a sealed envelope comprising means for supporting and rigidly gripping the end of said exhaust tube, means for heating a portion of said exhaust tube, a pressure member engaging said envelope, a lever carrying said pressure member at one end, spring means engaging the opposite end of said lever and resiliently urging the pressure member in a direction tending to stretch the exhaust tube while it is being heated, clamping jaws arranged to pinch the heated and stretched tube portion immediately upon stretching thereof, and means for causing said clamping jaws to close upon said tube portion, said last-named means including a switch member disposed in the path of movement of the said lever so as to be actuated by said lever. ²⁰

9. Apparatus for sealing an exhaust tube extending from a sealed envelope containing gas at a pressure above that of the surrounding atmosphere comprising means for supporting and rigidly gripping the end of said exhaust tube, ⁵ means for heating a portion of said exhaust tube while the said tube portion is exposed to the said surrounding atmosphere, means engaging said bulb and tending to twist the exhaust tube while it is being heated, the twisting force of said last-named means being of sufficient magnitude to rapidly twist and seal off the heated portion of the tube when it becomes sufficiently plastic to be thus deformed but before said tube portion becomes sufficiently plastic to be ruptured by the internal gas pressure, and means ¹⁰ for preventing additional heating of said tube which would render it sufficiently plastic to be ruptured by said internal gas pressure.

CERTIFICATE OF CORRECTION.

Patent No. 2,295,034.

September 8, 1942.

WALTER J. GEIGER, ET AL.

It is hereby certified that error appears in the printed specification of the above numbered patent requiring correction as follows: Page 3, second column, line 63, for "slide 90" read --slide 89--; line 64, after "upward" insert --from slide 90--; and that the said Letters Patent should be read with this correction therein that the same may conform to the record of the case in the Patent Office.

Signed and sealed this 1st day of December, A. D. 1942.

Henry Van Arsdale,
Acting Commissioner of Patents.
